G. W. GAGE

DRILLING MACHINE WITH SECTIONAL CRANK

Filed June 7, 1926

George W. Gage,

INVENTOR

INVENTOR
BY *Victor J. Evans*

ATTORNEY

P. J. Hickey.

WITNESS:

UNITED STATES PATENT OFFICE.

GEORGE WELLINGTON GAGE, OF PARNASSUS, PENNSYLVANIA.

DRILLING MACHINE WITH SECTIONAL CRANK.

Application filed June 7, 1926. Serial No. 114,373.

This invention relates to improvements in drilling machines, the general object of the invention being to provide a frame with a solid boxing and a sectional crank shaft 5 rotatably mounted in the boxing, with gears for rotating the bit shaft from the crank shaft.

This invention also consists in certain other features of construction and in the combination and arrangement of the several parts, to be hereinafter fully described, 10 illustrated in the accompanying drawings and specifically pointed out in the appended claim.

15 In describing my invention in detail, reference will be had to the accompanying drawings wherein like characters denote like or corresponding parts throughout the several views, and in which:—

20 Figure 1 is an elevation with parts in section, of the invention.

Figure 2 is a section on line 2—2 of Figure 1.

In these views, 1 indicates the frame which 25 is provided with the opening 2 and the boss 3 projecting into the opening, with the socket in the boss in alignment with the bore 4 formed in the outer part of the frame, this boss and the socket forming bearings for the 30 shaft 5 which is adapted to be attached to the tool or bit and which passes through the opening 2. A beveled gear 6 is attached to that part of the shaft which passes through the opening 2. A transversely arranged bore 35 7 is arranged in the frame and its side extensions 8 and a sleeve 9 is rotatably mounted in this bore. The inner end of a crank 10 projects into each end of the sleeve and these cranks are attached to the sleeve by the pins 11. Thus the sleeve and cranks form a sectional double crank. A beveled gear 12 is 40 fastened to the double crank by one of the pins 11 and this gear meshes with the gear 6. A collar 13 is fastened to the double crank

45 arranged on the crank between an extension 8 and the collar and tends to hold the gear 12 in mesh with the gear 6. A hollow stem 15 is adjustably connected to a stud 16 threaded in the frame and a breast plate 17 is fastened 50 to the outer end of the stem. Handles 18 are rotatably connected with the extremities of the double crank by the nuts 19.

From the foregoing, it will be seen that I have produced a simple form of drill, the 55 bit of which is rotated by turning a double crank, the motion of the crank being transmitted to the bit carrying member by gears. By making the crank in sections, it can be placed in the bore of the frame so that the 60 frame can be made solid.

It is thought from the foregoing description that the advantages and novel features of my invention will be readily apparent.

I desire it to be understood that I may 65 make changes in the construction and in the combination and arrangement of the several parts, provided that such changes fall within the scope of the appended claim.

What I claim is:—

A drilling device of the class described, 70 comprising a frame having a transverse bearing bore formed therein, a sleeve rotatably mounted in the bore and having its ends projecting therefrom, cranks having their inner 75 ends extending into the ends of the sleeve, a gear on one end of the sleeve, a collar on the other end of the sleeve, pins for connecting the gear and collar to the sleeve and the sleeve to the cranks, a bit carrying shaft 80 journaled in the frame, a gear on said shaft meshing with the gear on the sleeve and a spring on the sleeve and bearing against the collar for holding the parts with the gears in mesh.

85 In testimony whereof I affix my signature.

GEORGE WELLINGTON GAGE.
